RADIO DIAL MECHANISM

Leslie F. Curtis and Kenneth L. Henderson,
Springfield, Mass., assignors to United Ameri-
can Bosch Corporation, Springfield, Mass., a
corporation of New York

Application October 1, 1935, Serial No. 43,052

7 Claims. (Cl. 116—124.1)

This invention relates to radio tuning dials, and more particularly to illuminated dials bearing a plurality of frequency band scales. In the past there has been great difficulty in recording the exact dial setting of a station on the higher frequency bands. Requirements of pleasing cabinet design and esthetic appearance have necessitated dial scales which were too small and which had inadequate division marks for the higher frequency scales. It quite frequently occurs that many stations are located between two division marks and there is no accurate way of recording the setting for each station. In the invention herein described a novel vernier indicator is provided which may be read in conjunction with the main scale to accurately note the exact dial setting for a given station.

An object of this invention is to provide a tuning dial which is more efficient in operation and more pleasing in appearance.

Another object is to provide a dial which will more accurately indicate the exact setting of a station.

A further object is to provide a multiple frequency band dial which indicates the particular band being used.

Still a further object is to provide an illuminated dial structure in which the lamps are more accessible for replacement.

Other objects and advantages will in part be specifically set forth and in part be obvious when the following specification is read in connection with the accompanying drawings, in which:

Fig. 1 is a front view of the dial and supporting frame; Fig. 2 is a horizontal section taken on line 2—2 of Fig. 1; Fig. 3 is a front view of the driving disk, showing the shutter and control for the dial mechanism; and Fig. 4 is a front view of the assembly showing the combined vernier and masking disk in position.

Referring in more detail to Fig. 1, the numeral 1 indicates a frame member of sheet metal bent to form rearwardly extending walls on all four sides thereof, and having attaching brackets 2 bent from the vertical side walls. Supported interiorly against the front face of the frame is a sheet of glass, retained by spring clips 4, as shown in Fig. 2. Etched, or otherwise indented in the inner face of the glass 3 are the numerals and division marks of four separate frequency bands. The numerals and dial face are backed by an opaque material, with the semicircular areas overlying the paths of the various indicators left transparent. Around the periphery of the dial are the vernier numerals 1 to 59 inclusive and

immediately below each of these numerals is a small pin hole 5 through the opaque material, and through which light is periodically visible in connection with the vernier action to be explained later. The vertical side walls of the frame 1 are cut to allow the strips 6 to be bent out and form supports for the light socket clips 7 and lights 8. The light beams enter the edges of the glass 3 and pass laterally through the glass to strike the etched dial numerals, which then appear as luminous numerals against a dark background and provide a very pleasing appearance.

The dial mechanism is best seen in Fig. 2 and following figures. A driving disk 9, having a milled edge, is attached to the condenser shaft 10 of a radio chassis by a hub 11 which projects from both faces of the disk 9. The outer face of the driving disk is painted white to obtain maximum light reflection for a reason later explained. A rubber covered roller 12 bears against the milled edge of disk 9 (Fig. 3) and is in turn driven by a metal roller 13 having a milled periphery. The roller 13 is fastened on a shaft 14 which may be driven by any suitable tuning knob. One half of a split collar 15 is fastened to the hub 11, the other half being attached to the sleeve 16 of a rotatable shutter 17. The two halves of the split collar 15 are joined by a coil spring 18. The shutter is rotatable to four positions, corresponding to the four frequency bands of the usual multi-band receiver, and is actuated by the shaft 19 of a band changing switch through the following means. A flexible cord 20 is secured at one end to studs 21 mounted near the rim of drive disk 9. The cord is passed under the hub 11, over and around the eccentric pulley 22 which is mounted on switch shaft 19. From the pulley 22, the cord is trained under the shutter sleeve 16, and over to a stud 23 fastened near the rim of shutter 17. Four apertures 24, 25, 26, and 27 are provided in the shutter 17 (Fig. 3) with each backed by a different colored translucent member, and the entire shutter is finished in black to avoid light reflection. The showing in solid lines in Fig. 3 represents the terminal position of the shutter when the highest frequency band is in use, while the dotted showing indicates the shutter position for the next lower band. Positions for the remaining two bands are not shown, in the interests of simplicity, but as seen in Fig. 3 the shutter 17 continues to move counter-clockwise in increments equaling that illustrated. When the drive disk 9 is rotated, the shutter moves with it, remaining in the same relative positions for the remaining two bands.

angular position due to the action of the cord 20 about the several centers. Frictionally secured to the end of hub 11, in front of the shutter 17, is a black masking disk 28, as shown 5 in Fig. 4. Indicating orifices 29, 30, 31, and 32 are punched in the disk, and twelve equally spaced vernier slots 33 extend radially inward from the periphery.

Operation

10 When the dial is assembled, the masking disk 28 and the frame 1 are adjusted so that their centers are coincidental. This is accomplished by first rotating masking disk 28 until the indicating orifices 29, 30, 31, and 32 are in a horizontal line. The masking disk and the frame are then aligned with respect to the indicating orifices so that the edges 34, 35, 36, and 37 (Fig. 1) of the opaque design on glass 3 bisect the 15 orifices 30 and 31 in disk 28, and also so that outermost points of orifices 29 and 32 in disk 28 are equidistant from the circular edge of the opaque design on glass 3. Then one of the pin holes 5 (Fig. 1) will be illuminated. Upon 20 rotation of the driving disk 9, this pin hole is darkened and one five points distant is subsequently illuminated, the progression being 1—6—11—16 . . . 56—2—7—12 etc. Approximately two degrees of scale travel results in one 25 revolution of the light spot around the dial. If a finer vernier action is desired, the masking disk 28 may have any greater number of slots 33 which is evenly divisible into sixty. When sixty 30 slots are provided, each pin hole 5 is illuminated 35 in regular sequence; however, proper assembly adjustment becomes increasingly difficult as the skip interval is reduced.

When the various dial elements are positioned as shown in Figs. 3 and 4, the hole 24 of shutter 40 17 will be in alignment with the indicator hole 29 of masking disk 28 and a diamond of colored 45 light will be visible as an indicator on the high frequency or lower scale, as shown in Fig. 1. When the shaft 19 of the wave change switch 50 is turned clockwise, the holes 25 and 30 will be aligned and indicate the next adjacent scale. Continued clockwise turning will successively align the holes 32—27, and 31—26, to indicate 55 the remaining two upper scales. Since an illuminated indicator or pointer appears only adjacent the particular scale in use and moves with the rotation of the tuning knob, there can be no uncertainty on the part of the operator as to which band to read. As the masking disk 28 which 60 directly underlies the dial glass 3 is painted black, no light other than the colored indicator light is visible through the transparent semicircular openings and the dial numerals and marking appear luminescent against a black background 65 with the colored indicator light adjacent the markings.

It will be obvious that many changes and modifications may be made by anyone skilled in the art, without departing from the spirit and scope 65 of the invention as expressed in the following claims.

We claim:

1. In an illuminated radio dial mechanism having a plurality of tuning scales, a driving disk, a hub extending from said driving disk, a masking disk secured to said hub and having a plurality of spaced indicating orifices, a shutter rotatably attached to said hub intermediate said disks and having a plurality of apertures therein, a 70 flexible cord attached to said driving disk and

said shutter, and means for operating said cord, whereby said shutter may be rotated relative to said masking disk to align a shutter aperture with an indicating orifice in said masking disk to produce an indicating light spot on one of said tuning scales.

2. In an illuminated radio dial mechanism having a plurality of tuning scales, a driving disk, a hub extending from said driving disk, a masking disk secured to said hub and having a plurality of indicating orifices of different radial spacing, a shutter rotatably attached to said hub intermediate said disks and having a plurality of apertures therein radially spaced to accord with said indicating orifices, a flexible cord attached to said driving disk and said shutter, and means for operating said cord, whereby said shutter may be rotated relative to said masking disk to align a shutter aperture with an indicating orifice in said masking disk to produce an indicating light spot on one of said tuning scales.

3. In an illuminated radio dial mechanism having a plurality of tuning scales, a driving disk, a hub extending from said driving disk, a masking disk secured to said hub and having a plurality of spaced indicating orifices, a shutter rotatably attached to said hub intermediate said disks and having a plurality of apertures therein, a spring urging said shutter in one direction, a flexible cord attached to said driving disk and 30 said shutter, said cord being maintained under tension by said spring-urged shutter, and means for operating said cord, whereby said shutter may be rotated relative to said masking disk to align a shutter aperture with an indicating orifice in said 35 masking disk to produce an indicating light spot on one of said tuning scales.

4. In an illuminated radio dial mechanism having a plurality of tuning scales, a driving disk, a hub extending from said driving disk, a masking disk secured to said hub and having a plurality of spaced indicating orifices, a shutter rotatably attached to said hub intermediate said disks and having a plurality of apertures therein, a spring urging said shutter in one direction, a 45 flexible cord attached to said driving disk and said shutter, said cord being maintained under tension by said spring-urged shutter, a shaft carrying an eccentric pulley, a portion of said cord trained around said pulley, whereby said 50 shaft may be actuated to rotate said shutter relative to said masking disk to align a shutter aperture with an indicating orifice in said masking disk to produce an indicating light spot on one of said tuning scales. 55

5. In an illuminated radio dial, a light source, a vernier indicator comprising a plurality of light-transmitting pin holes, a rotatable masking disk positioned intermediate said light source and said dial, and a plurality of slots in said disk, 60 whereby said slots and said pin holes cooperate to produce a point of light which advances from one pin hole to another upon unidirectional rotation of said masking disk.

6. In an illuminated radio dial, a light source, 65 operating mechanism and an indicator for said dial, a vernier indicator comprising a marking member positioned intermediate said light source and said dial, a plurality of slots in said member, and a plurality of pin holes arranged in regular 70 sequence upon said dial, whereby said slots and said pin holes cooperate to produce a point of light which advances along said pin holes at a speed greater than the speed of said indicator.

7. In an illuminated radio dial, a light source,

operating mechanism and an indicator for said dial, a vernier indicator comprising a masking member positioned intermediate said light source and said dial, a plurality of slots in said member, and a plurality of pin holes arranged in regular sequence upon said dial, the number of said pin holes being equal to a number $n \pm 1$, and the

number of said slots being equal to any number evenly divisible into n , whereby said slots and said pin holes cooperate to produce a point of light which advances along said pin holes at a speed greater than the speed of said indicator.
